(57) **CLAIM**

We claim the ornamental design for an animated responsive display on a joystick, as shown and described.

DESCRIPTION

FIG. 1 is a first image in a first sequence of an animated responsive display on a joystick, when the joystick is in a first position;

FIG. 2 is a second image thereof, when the joystick is in a second position;

FIG. 3 is a third image thereof, when the joystick is in a third position;

FIG. 4 is a fourth image thereof, when the joystick is in the third position;

FIG. 5 is a fifth image thereof, when the joystick is in the third position;

FIG. 6 is a sixth image thereof, when the joystick is in the third position;

FIG. 7 is a seventh image thereof, when the joystick is in the third position;

FIG. 8 is an eighth image thereof, when the joystick is in the second position;

FIG. 9 is a ninth image thereof, when the joystick is in the second position;

FIG. 10 is a tenth image thereof, when the joystick is in the second position;

FIG. 11 is an eleventh image thereof; and a first image in a second sequence of an animated responsive display on a joystick, when the joystick is in the first position;

FIG. 12 is a second image thereof, when the joystick is in a fourth position;

FIG. 13 is a third image thereof, when the joystick is in a fifth position;

FIG. 14 is a fourth image thereof, when the joystick is in the fifth position;

FIG. 15 is a fifth image thereof, when the joystick is in the fifth position;

(Continued)

FIG. 16 is a sixth image thereof, when the joystick is in the fifth position;

FIG. 17 is a seventh image thereof, when the joystick is in the fifth position;

FIG. 18 is an eighth image thereof, when the joystick is in the fourth position;

FIG. 19 is a ninth image thereof, when the joystick is in the fourth position; and,

FIG. 20 is a tenth image thereof, when the joystick is in the fourth position.

In a first embodiment, the appearance of the animated responsive display on a joystick sequentially transitions between images shown in FIGS. 1-11. In a second embodiment, the appearance of the animated responsive display on a joystick sequentially transitions between the images shown in FIGS. 11-20. The period in which one image transitions to another forms no part of the claimed design.

The surface lines shown between the outer circumference of the responsive display and the first set of inner broken lines depict a translucent portion of the responsive display, and the surface lines do not convey a particular surface profile, surface texture, or finish. The broken lines showing the remainder of the joystick are for environmental purposes only and form no part of the claimed design.

1 Claim, 10 Drawing Sheets
